Inventor

Bennie Stieger
By his Attorneys
Masow Fenwick Lawrence,

UNITED STATES PATENT OFFICE.

BENNIE STIEGER, OF NEW YORK, N. Y.

DESIGN FOR A LIGHTING-FIXTURE MEMBER OR ARTICLE OF SIMILAR NATURE.

60,502.

Specification for Design.

Patented Feb. 28, 1922.

Application filed June 16, 1920. Serial No. 389,505. Term of patent 3½ years.

To all whom it may concern:

Be it known that BENNIE STIEGER, a citizen of Russia, residing at New York, in the county of New York and State of New York, have invented a new, original, and ornamental Design for Lighting-Fixture Members or Articles of Similar Nature, as shown in the accompanying drawing and described in the following specification.

Figure 1 is a plan view of a lighting fixture member embodying my invention.

Figure 2 is a side elevation of the same, and

Figure 3 is a cross sectional view for showing the character of the depressions in the surface of the said lighting fixture member.

I claim:

The ornamental design for a lighting fixture member or article of similar nature as shown.

BENNIE STIEGER.
